REEL RACK

George F. Lyman, South Hadley, Mass., assignor to Data Packaging Corp., Cambridge, Mass., a corporation of Massachusetts

Filed June 1, 1965, Ser. No. 85,520

Term of patent 14 years

(Cl. D33—3)

FIG. 1 is a perspective view of a reel rack showing my design;

FIG. 2 is a side elevational view on a reduced scale;

FIG. 3 is a cross-sectional view of the rack in side elevation and taken along the lines 3—3 of FIG. 4;

FIG. 4 is a top view on a reduced scale;

FIG. 5 is a front view on a reduced scale;

FIG. 6 is a back view on a reduced scale; and

FIG. 7 is a bottom view on a reduced scale.

I claim:

The ornamental design for a reel rack, as shown.
